CHARGE FORMING DEVICE

Fred E. Aseltine, Dayton, Ohio, assignor, by
mesne assignments, to General Motors Corpora-
tion, Detroit, Mich., a corporation of Dela-
ware

Application May 22, 1931, Serial No. 539,282

11 Claims. (Cl. 123—124)

This invention relates to charge forming de-
vices for internal combustion engines, and more
particularly to devices of this character which
comprise a plurality of primary carburetors, each
5 of which delivers a primary mixture of air and
fuel to one of a plurality of secondary mixing
chambers located adjacent the engine intake
ports and in which the primary mixture is mixed
with additional air under certain operating con-
ditions.

A device of this character is shown in the co-
pending application of Fred E. Aseltine, et al.,
Serial No. 288,683, filed June 27, 1928.

It is the object of this invention to provide
15 means to insure a high velocity of flow through
the secondary mixing chambers under all oper-
ating conditions so that puddling of the fuel in the
secondary mixing chambers will be prevented,
and which is so constructed that the area of the
20 intake passages will not be sufficiently restricted
at any point to materially reduce the engine
power. While this invention is more particularly
adapted for use with engines of the L-head type,
it will be understood that it is also applicable to
25 other types of engines, for by preventing the
precipitation of fuel in the secondary mixing
chambers as above described, it improves the
distribution of fuel mixture to the various engine
cylinders and by increasing the velocity of flow
30 of the mixture, improves the operation of any
type of engine during the acceleration of the en-
gine and other operating conditions.

Further objects and advantages of the present
invention will be apparent from the following de-
35 scription reference being had to the accompan-
ying drawing wherein a preferred embodiment of
one form of the present invention is clearly shown.

In the drawing:

Fig. 1 is a longitudinal section through a charge
40 forming device constructed in accordance with
the present invention.

Fig. 2 and 3 are sections on the lines 2—2 and
3—3 respectively, of Fig. 4.

Fig. 4 is a longitudinal section through an in-
45 sert adapted to fit within the outlet branches of
the manifold which forms part of the charge
forming device.

Fig. 5 is a view similar to Fig. 4, showing a
modified form of valve.

50 The device disclosed comprises a main air mani-
fold 10, having three outlet branches, the middle
branch 12 being shown herein. Each outlet
branch communicates with one of the ports of
a multicylinder engine and each is provided with
55 an attaching flange 14 for securing the manifold

to the engine in the conventional manner, while
a flange 16 is provided on the manifold inlet for
securing the carburetor unit thereto. Each
branch of the manifold is not shown in detail
herein as all are alike in construction, one only 5
of such branches being shown for the sake of
simplifying the disclosure.

The carburetor unit comprises a main housing
18, having a flange 20 adapted to be secured in
any desirable way to the flange 16, while an air 10
inlet coupling 22 is secured in an opening in the
housing to admit air thereto. A casting 24, in
which the passages for conducting fuel from the
fuel bowl to the nozzles are formed, is secured to
the bottom wall of the main housing and a sheet 15
metal fuel bowl 26 is held tight against a shoul-
der 28 on the main housing in any suitable man-
ner. Fuel is conducted to the bowl 26 from a
main source of supply and a float 30 maintains a
substantially constant level in the bowl in the 20
usual way.

Fuel is conducted from the bowl to a plurality
of fuel nozzles 32, which project into the primary
mixing chambers 34 by means which are fully
disclosed in the above mentioned application, but 25
which have been omitted herein for the sake of
simplifying the disclosure, the structure of the
fuel supply passages and the like being entirely
immaterial with respect to the present invention.
There are three of the nozzles 32 and chambers 30
34, each of the chambers being adapted to com-
municate with one of three primary mixture pas-
sages 36, which passages register with conduits
which are adapted to convey the primary mixture
to secondary mixing chambers formed in the out- 35
let branches of the manifold as more fully de-
scribed later. Only one of the conduits referred
to is shown herein, namely, that associated with
the middle outlet branch of the manifold. This
conduit is in the form of a sheet metal tube 38, 40
fixed in position in the manifold and delivering
primary mixture at the point adjacent the bottom
of the middle outlet branch of said manifold, as
clearly shown in Fig. 1.

As indicated in Fig. 1, the primary mixing 45
chambers constitute the enlarged ends of the pas-
sages 36 and positioned adjacent the nozzles and
posterior thereto at the posterior ends of the mix-
ing chambers are restrictions 40, these restrictions
operating to reduce the velocity of flow past the 50
nozzles to prevent the formation of a substan-
tial velocity head at the nozzles.

The flow of mixture through the primary mix-
ture passages is controlled by a single throttle
valve 42 which extends across all of said mixture 55

passages and is provided with grooves 44, which register therewith. The operating mechanism for the throttle is not disclosed herein and is not material to the present invention.

5 Air is admitted through the coupling 22 and is controlled by a suction operated valve 46, normally held closed by spring 48, received between the valve and the flange 50, projecting from a sleeve 52, slideable on a fixed sleeve 54, which is 10 secured in the housing in any desirable manner and operates as a guide for the valve stem 56. The opening movements of the valve 46 are retarded to insure the correct mixture during the acceleration period by means of a dashpot comprising the cylinder 58, formed in the casting 24, and the piston 60, secured to the end of the valve stem 56. Air passing the valve 46 enters the main air chamber 62, which supplies air to the primary mixing chambers through an opening 64 in the 15 floor of said air chamber and to the secondary mixing chambers in the manifold through a secondary air passage 66, which communicates with the inlet of the manifold 10.

The flow of air through the latter passage is 20 controlled by manual and suction operated valves 68 and 70 respectively, which are secured to shafts 72 and 74 respectively, both of which are journaled in the main housing. The mechanism for operating the valves 68 and 70 is not disclosed 25 herein since this mechanism constitutes no part of the present invention. However, in order to enable a better understanding of the general operation of the device, the operation of these valves will be briefly described and reference may 30 be had to the above mentioned application for the specific disclosure of the operating mechanism. The primary throttle 42 is connected to the valve 68 by a lost motion connection, while the valve 70 is operated entirely by engine suction and begins to operate only after the valve 35 68 starts to open. The lost motion connection may be varied to cause the valve 68 to begin opening at various engine speeds, but ordinarily is so constructed that this valve starts to open 40 when the engine is running at a speed sufficient to operate the vehicle at substantially 20 to 25 miles per hour on the level. The opening of the valve 70 is retarded by means not disclosed herein in order to restrict the flow of air temporarily 45 on opening movements of the throttle in order to secure the desired engine operation during the acceleration period.

The primary mixture which is supplied to the 50 secondary mixing chambers formed in the outlet branches of the manifold is mixed with air in these secondary mixing chambers at all speeds above that at which the valve 68 is opened, but at lower speeds, the primary mixture is carried into the cylinders without dilution by additional 55 air which is admitted through the passage 66. At these lower speeds particularly, and when the engine is operating under heavy load with the throttle open to a considerable extent, the velocity of flow through the secondary mixing 60 chambers is so low that fuel tends to collect on the walls of the secondary mixture passages between the outlets of the various primary mixture conduits and the cylinders. The fuel which tends to collect in this manner is picked up irregularly and carried into the engine in rather large 65 drops or particles of varying size so that the supply of fuel to the various cylinders is irregular and uneven. As a result of this irregular supply and uneven distribution of the fuel, the engine 70 runs erratically and it is the primary purpose of 75

this invention to provide means which is effective under all operating conditions to prevent the above described action taking place.

In order to accomplish this purpose, there is 80 provided in each of the outlet branches of the manifold unit comprising a sleeve 90 adapted to fit tightly within the associated outlet branch and provided with a flange 92 projecting therefrom which, when the device is assembled, is clamped between shoulders 94 and 96 on the 85 manifold and the engine block, respectively. Rotatably journaled in the sleeve 90 are two shafts 98 and 100 to which are secured in any desirable way, butterfly valves 102 and 104, the valve 102 being unbalanced with respect to the shaft 98, 15 while the valve 104 is provided with holes 106 on the lower half of such valve, this construction also unbalancing the valve 104 to some extent, but not as much as is the valve 102. Also if desired, the holes in the valve 104 may be omitted entirely, 20 these holes being provided primarily to permit the passage of the mixture from the conduit 38 and it is obvious that this mixture could flow beneath the valve, since the valve is not as great 25 in area as the area of the passage within the sleeve.

These valves are connected together by a link 108 pivotally connected to lugs 110 and 112 projecting from the valves 102 and 104, respectively, the link passing through a slot in the valve 102. 30 The valves are held in the position shown in Fig. 4 by a spring 114, surrounding the shaft 98 and having one end extending over a rod 116 mounted in the sleeve and the other end engaging the face of the valve 102. As the valves are opened by 35 engine suction, the spring will be tensioned so that on reduction of suction, the spring is effective to move the valves toward closed position.

The operation of this device should be obvious. 40 As the engine is operating at low speed with the valves 68 and 70 closed, the valves 102 and 104 restrict the area of the passage through the secondary mixing chamber to such an extent that the velocity of flow therethrough is relatively 45 high and any fuel which tends to precipitate out 50 of the mixture and collect on the walls will be carried through the mixing chamber so rapidly by the high velocity of flow that the precipitation as described, is substantially prevented. It is necessary that this restriction be reduced as 55 the throttle and valves 68 and 70 are opened or the volumetric efficiency of the engine will be materially cut down. Therefore, the valves 102 and 104 are adapted to operate automatically to 60 vary the area of the passage through the secondary mixing chamber in accordance with the variations in engine suction. Since the valve 102 is unbalanced, the blast of air passing through the secondary mixing chamber will move said valve toward open position and the valve 104 65 which is movable therewith through the medium of link 108, being more nearly a balanced valve than the valve 102, acts as a brake to prevent rapid fluttering of the valve 102. If the valve 102 were not provided with this means to retard 70 its motion, it would flutter so rapidly because of rapid changes in suction which occur in engine pulsations that the device would soon be worn out. It will be obvious that the size of the holes 106 in valve 104 may be varied if desired. 75 This device is substantially effective to prevent any accumulation of fuel by puddling at points posterior to the outlet of the mixture conduit 38 with a resultant increase in efficiency of engine operation.

While the form of embodiment of the present invention as herein disclosed, constitutes a preferred form, it is to be understood that other forms might be adopted, all coming within the scope of the claims which follow.

5 What is claimed is as follows:

1. An intake manifold for a multi-cylinder internal combustion engine having a plurality of intake ports, comprising a plurality of outlet branches adapted to communicate with said intake ports, fuel supply conduits discharging fuel into such outlet branch and valves in said branches controlling the velocity of flow therethrough past the discharge end of the fuel supply conduit, and means for cushioning the movement of said valves.

2. An intake manifold for a multi-cylinder internal combustion engine having a plurality of intake ports, comprising a plurality of outlet branches adapted to communicate with said intake ports, fuel supply conduits discharging fuel into such outlet branch and valves in said branches controlling the velocity of flow therethrough past the discharge end of the fuel supply conduit, and means for retarding the opening and closing movement of said valves.

3. An intake manifold for a multi-cylinder internal combustion engine having a plurality of intake ports, comprising a plurality of outlet branches adapted to communicate with said intake ports, an unbalanced suction operated valve in each of said outlet branches and a balanced valve connected to each of said unbalanced valves, whereby the movements of the latter are retarded.

4. An intake manifold for a multi-cylinder internal combustion engine having a plurality of intake ports, comprising a plurality of outlet branches adapted to communicate with said intake ports, conduits adapted to supply fuel to the manifold branches, a valve in each of said branches adapted to regulate the velocity of flow past the end of the conduit associated therewith, and means for cushioning both the opening and closing movements of the valves.

5. A charge forming device for internal combustion engines comprising a primary mixture passage, means for supplying fuel and air to said primary mixture passage, a secondary mixing chamber to which the primary mixture passage is adapted to supply a primary mixture of fuel and air, means in said secondary mixing chamber for accelerating the flow therethrough, said means comprising a plurality of suction operated valves, one of which is constructed to operate as a brake to retard the opening movements of the other.

6. A charge forming device for internal combustion engines comprising a primary mixture passage, means for supplying fuel and air to said primary mixture passage, a secondary mixing chamber to which the primary mixture passage is adapted to supply a primary mixture of fuel

and air, means in said secondary mixing chamber for accelerating the flow therethrough, said means including an unbalanced valve operated by engine suction, and another valve effective to retard the opening movements of the first valve.

7. A charge forming device for internal combustion engines comprising a primary mixture passage, means for supplying fuel and air to said primary mixture passage, a secondary mixing chamber to which the primary mixture passage is adapted to supply a primary mixture of fuel and air, means in said secondary mixing chamber for accelerating the flow therethrough, said means including an unbalanced valve operated by engine suction, and another valve connected to the first valve, said last named valve being effective to retard the opening movements of the first valve.

8. A charge forming device for internal combustion engines comprising a primary mixture passage, means for supplying fuel and air to said primary mixture passage, a secondary mixing chamber to which the primary mixture passage is adapted to supply a primary mixture of fuel and air, means in said secondary mixing chamber for accelerating the flow therethrough, said means including two valves unbalanced to different degrees and operable by engine suction.

9. A charge forming device for internal combustion engines comprising a primary mixture passage, means for supplying fuel and air to said primary mixture passage, a secondary mixing chamber to which the primary mixture passage is adapted to supply a primary mixture of fuel and air, means in said secondary mixing chamber for accelerating the flow therethrough, said means including two valves unbalanced to different degrees operable, and means for connecting said valves whereby one valve operates as a brake upon the other.

10. A charge forming device for internal combustion engines comprising a primary mixture passage, means for supplying fuel and air to said primary mixture passage, a secondary mixing chamber to which the primary mixture passage is adapted to supply a primary mixture of fuel and air, means in said secondary mixing chamber for accelerating the flow therethrough, said means including a plurality of valves, one of which is located adjacent the outlet of the primary mixture passage to accelerate the flow past said outlet.

11. A charge forming device for internal combustion engines provided with means for forming a primary mixture of fuel and air, means adapted to convey this primary mixture to a plurality of secondary mixing chambers, means in the secondary mixing chambers adapted to accelerate the flow therethrough, said means comprising a plurality of suction operated valves, one of which is constructed to retard the opening movement of the other.

FRED E. ASELTINE.
